CONTROL SYSTEM FOR CIRCULATING FLUIDS

Lewis L. Cunningham, Minneapolis, Minn., assignor to Minneapolis-Honeywell Regulator Company, Minneapolis, Minn., a corporation of Delaware

Application November 18, 1933, Serial No. 698,639

7 Claims. (Cl. 236—91)

The present invention relates to the control of circulating fluids such, for example, as are employed in the control of temperature.

One of the objects of the present invention is 5 the provision of a system for controlling the flow of a temperature changing fluid to a temperature changing device, the control system being so arranged that the fluid is permitted to flow to the temperature changing device for successive 10 periods of substantially equal duration and varying the intervals between such periods. Preferably, the intervals between such periods are varied conformably to changes in some temperature condition, such as changes in the outdoor 15 temperature.

More specifically, one of the objects of the present invention is the provision of a steam heating system in which steam is permitted to flow to the radiators in successive cycles of 20 substantially equal duration and varying the intervals between the termination of one cycle and the initiation of the next succeeding cycle in accordance with some temperature condition, such as changes in the outdoor temperature. In 25 such a system, the unchanging periods of steam flow are predetermined so that each cycle of steam flow is only long enough to completely fill all of the radiators in the system and the steam flow is thereafter stopped so that each of the 30 radiators has a stored heat capacity corresponding to its size. The maximum length of time that the intervals between steam feeding periods may persist is limited, particularly in the control of hotels, etc. so that no one of the radiators can become cold and give the guests the impression that the rooms are underheated. This provision also constitutes an object of the 35 invention.

Another of the broader objects of the invention 40 is the provision of a system for controlling the flow of fluids wherein there is a variable demand, the system being so arranged that an initial maximum demand can never be made. For instance, in a heating system wherein a boiler 45 of limited steam storage capacity is connected to a large number of radiators, if all of the radiators are simultaneously placed in connection with the boiler, a large proportion of the steam will be drained off and the pressure will 50 therefore drop to a negligible value before the fire can be increased to meet the increased demand.

An object of the invention, therefore, is the provision of means for interposing a delay be- 55 tween the demand of two or more devices and

the actual supplying of fluid thereto. Specifically, upon a demand for steam, a plurality of valves are sequentially opened with an appreciable delay between the successive opening of the various valves so that the demand is gradually increased instead of starting out at the maximum.

A further object of the invention is the provision of a temperature changing system for a large building in which the building is divided into two or more zones depending upon variable demands on the various zones by reason of their being subjected to varying wind directions, wind velocities and solar radiation, and providing separate temperature changing devices and separate controls for each zone. Preferably, each of the various zone controls includes a thermostat which is affected by the outdoor temperature conditions to which the particular zone is subjected.

Another object of the invention is the provision of a temperature control system for a plurality of spaces in which the temperature changing means is controlled both by the average temperature in two or more of the spaces and by the outdoor temperature.

Other objects of the invention lie in the combination of the various above-mentioned systems to form various complete systems of temperature control and also include the various combinations and subcombinations of elements and their inter-relation.

Further objects of the invention will be evident from the following detailed description, accompanying drawings and appended claims.

For a more complete understanding of the invention, reference may be had to the following description and accompanying drawings, in which,

Fig. 1 is a schematic showing of the complete system of the present invention as applied to the heating of a large building, and

Fig. 2 is a diagrammatic showing of the control apparatus and circuits by which certain parts of the system of Fig. 1 are controlled.

Referring first to Fig. 1 of the drawings, a large building which it is desired to heat is generally indicated at 10. The building includes a basement 11 which contains a large steam boiler 12. The steam boiler 12 is heated by an oil burner 13 which in turn is controlled by a steam pressure responsive switching mechanism 14 that dominates the operation of the usual control box 15 through control wires 16. Power is supplied to the control box 15 through supply line 17.

The pressure responsive switching mechanism 14 operates normally to maintain a constant steam pressure in the boiler 12.

Steam from the boiler 12 first passes through 5 a diaphragm type pressure regulator 18 of well-known construction, then traverses an electrically operated valve 19 and passes through mains 20 and 21. The electrically operated valve 19 is controlled by a pressure responsive potentiometer 10 22 through a reversible motor mechanism 23. The reversible motor mechanism 23 and the electrically operated valve 19 preferably take the general form of mechanism shown in applicant's co-pending application Ser. No. 535,886 filed May 15 8th, 1931 which issued February 5, 1935, as Patent No. 1,989,972.

The function of pressure regulator 18 is to deliver steam from the boiler 12 to mains 20 and 21 at a constant reduced pressure. If there 20 should be a sudden demand on the boiler 12 for steam, it has been found that the diaphragm pressure regulator 18 will tend to gush and hunt before it finally settles down to deliver a steady reduced pressure to mains 20 and 21, and for 25 this reason, the electrically operable valve 19, which responds to variations in steam pressure on the outlet side of the pressure regulator 18, has been included whereby the valve 19 is slowly opened and closed upon changes in such pressure 30 sure to steady the action of the pressure regulator 18.

The mains 20 and 21 extend upwardly through the entire building 10 and terminate in the attic 24. A first riser 25 is connected to main 21 35 through an electrically controlled valve 26. This riser 25 extends downwardly through the building and supplies steam to radiators 27 located in rooms 28. A similar riser 29 is connected to main 21 through an electrically controlled valve 40 30 and supplies steam to radiators 31 located in rooms 32. The groups of rooms 28 and 32 are herein shown as comprising one of the several zones of the building 10, there being in actual practice a separate zone for each part of the 45 building that is affected differently by outside weather conditions. This zone has been shown as comprising two groups of rooms which are supplied with steam from a single main through two risers. In actual practice, depending upon the size of the building and the number of rooms contained in each zone, there may very well be a larger number of risers per zone and the two risers shown herein are to be understood as merely illustrative of one embodiment of the invention. The 50 electrically controlled valves 26 and 30 are controlled by a thermostatic device 33 which includes a bimetallic thermostatic actuating element 34 which responds to weather conditions outside of the building 10. Each of the rooms 28 and 32 is provided with a vent 35 and all these 55 vents 35 are connected to a suction fan 36 by means of pipes 37. The fan 36 operates to withdraw air from each and every one of the rooms 28 and 32 and discharges this air to the outdoor atmosphere. A thermostatic device 38 responds to the temperature of the air withdrawn from all of these rooms and in this manner responds to the average temperature of all of the rooms. The 60 vents 35 and piping 37 may be especially installed for this purpose or, in some cases, it will be possible to place the thermostat 38 so as to respond to air withdrawn from the various rooms for ventilating ducts which are already existent in the building.

70 The main 20 similarly supplies two risers 40

and 41 through electrically controlled valves 42 and 43. The riser 40 supplies steam to radiators 44 located in rooms 45, whereas the riser 41 supplies steam to radiators 46 located in rooms 47. Each of the rooms 45 and 47 is provided with a 5 vent 48 and all of these vents are connected to suction fan 36 through piping 49. A thermostatic device 50 responds to the temperature of the air withdrawn from the rooms 45 and 47 and a thermostatic device 51 which includes helical 10 bimetallic thermostatic element 52 is exposed to outside weather conditions and controls the operation of valves 42 and 43. These rooms, radiators, vents, etc. comprise a second zone similar in every manner to the first zone except that the 15 second zone is exposed to different weather conditions and the heating demand thereof therefore differs from the demand of the first zone.

The manner in which thermostatic devices 33 and 38 control valves 26 and 30 is exactly the 20 same as the manner in which thermostatic devices 50 and 51 control the valves 42 and 43 and, in the following detailed description, the complete control mechanism for only a single zone will be described but it is to be understood that 25 each and every other zone is supplied with a similar control mechanism.

Valve 26 is adapted to be controlled either manually or automatically by suitable switching mechanism. The manual switching mechanism 30 comprises a flexible blade 55 which is normally in engagement with a contact arm 56 and a second flexible blade 57 which is normally in engagement with a contact arm 58. A manual operator 59 is provided with a finger 60 which, upon proper 35 manipulation, will engage flexible blade 55 to move it out of engagement with contact arm 56 and into engagement with a contact arm 61 or will engage flexible blade 57 to move it out of engagement with contact arm 58 and into engagement 40 with a contact arm 62. Contact arm 56 and flexible blade 57 are electrically connected. The automatic switching mechanism comprises a flexible blade 63 which is normally biased into engagement with a contact 64 but is adapted to 45 be flexed into engagement with a contact 65.

With the parts in the position shown, the manual operator 59 is in automatic position and flexible blade 63 is engaged with contact 64 so that a closing circuit for valve 26 is completed. This closing circuit is as follows: line 66, flexible blade 55, contact arm 56, flexible blade 57, contact arm 58, wire 67, flexible blade 63, contact 64, wire 68, wire 69 and valve 26 to line 72. When flexible blade 63 is flexed into engagement with 55 contact 65, a valve opening circuit is completed for valve 26 as follows: line 66, flexible blade 55, contact arm 56, flexible blade 57, contact arm 58, wire 67, flexible blade 63, contact 65, wire 76, wire 77, and valve 26 to line 72. If it should be desired 60 to manually open valve 26, manual operator 59 is manipulated so that finger 60 engages flexible blade 55 to move it from engagement with contact arm 56 and into engagement with contact arm 61 to complete a valve opening circuit for 65 valve 26 as follows: line 66, flexible blade 55, contact arm 61, wire 81, wire 77, and valve 26 to line 72. Similarly, if it be desired to manually close valve 26, manual operator 59 is manipulated to bring finger 60 into engagement with flexible 70 blade 57 to move the latter from engagement with contact arm 58 and into engagement with contact arm 62. A closing circuit for valve 26 is thereby established as follows: line 66, flexible blade 55, contact arm 56, flexible blade 57, con- 75

tact arm 62, wire 82, wire 69, and valve 26 to line 12.

If desired, indicating lamps can be suitably associated with the valve 26, in any of the well-known manners, to indicate whether the valve is open or closed.

The valve 30 is controlled by a similar switching mechanism and circuit arrangement, the parts of which have been referenced 55A and 82A inclusive to correspond with the similar parts and switches for operating valve 26. It will be understood that there could be a larger number of risers and valves in each zone and that there should be one of these switching systems for each and every valve. The automatic switches are controlled by a timer mechanism which includes a timer motor having a rotor 83 and a field winding 84. The rotor 83 drives a cam shaft 85 through suitable gear reduction indicated generally as 86. The cam shaft 85 carries two relatively adjustable cams 87 and 88 which, upon rotation of cam shaft 85, successively engage the extended ends of flexible blades 63A and 63 to flex them into engagement with their contacts 65A and 65 and, upon continued rotation of cam shaft 85, the flexible blades 63A and 63 will ride off the end of cam 87 and move back into engagement with contacts 64A and 64. The flexible blades 63A and 63 are spaced about cam shaft 85 so that they are successively or sequentially operated by cams 87 and 88 for a purpose which will hereinafter appear. Cam shaft 85 also carries a stopping switch cam 89 and a maintaining switch cam 90 which are provided with lobes 91 and 92 respectively. Lobe 91 operates a push rod 93 which is adapted to engage a switch arm 94 and move the same to the position shown in the drawings wherein it is latched by the hooked end 95 of an armature 96 which is pivoted at 97. Armature 96 is adapted to be attracted by an electromagnetic coil 98 and is biased away from electromagnetic coil 98 by a spring 99. Switch arm 94, when released by latch 95, is adapted to engage a switch arm 100. Lobe 92 operates a push rod 101 which engages a switch arm 102 and moves the same out of engagement with a switch arm 103.

Upon momentary energization of electromagnetic coil 98, armature 96 is attracted and the latch 95 thereof releases switch arm 94 for movement into engagement with switch arm 100. Field coil 84 of the timer motor is thereupon energized by a circuit as follows: line 105, wire 106, wire 107, switch arm 94, switch arm 100, wire 108, field winding 84, wire 109 and wire 110 to line 111. Energization of field winding 84 causes rotation of cam shaft 85 in a counter-clockwise direction as viewed from the left in Fig. 2. Initial rotation of cam shaft 85 in this direction moves lobe 92 from under push rod 101 and allows this push rod to move downwardly whereupon switch arm 102 moves into engagement with switch arm 103 and establishes a maintaining circuit for field winding 84 which is independent of switch arms 94 and 100. This maintaining circuit is as follows: line 105, wire 106, wire 107, wire 112, switch arm 102, switch arm 103, wire 113, wire 108, field winding 84, wire 109 and wire 110 to line 111. Shortly thereafter cam 88 engages flexible blade 63A and moves the same into engagement with contact 65A to open valve 30 whereupon steam traverses riser 29 and flows to the various radiators 31. Continued rotation of cam shaft 85 thereafter causes cam 88 to engage flexible blade 63 and move the same into engage-

ment with contact 65 whereupon valve 26 is opened and steam flows through riser 25 and to the various radiators 27. The valves 30 and 26 remain open until cam 87 rotates from under flexible blades 63A and 63 respectively whereupon these blades return to the position shown in Fig. 2 and cause their respective valves 30 and 26 to close. In this manner, all of the valves in a single zone are opened with a time interval between the successive opening of any two valves so that the full demand of a single zone is never initially placed on the boiler. In other words, the demand of a single zone for steam from the boiler 12 is gradually built up instead of instantly increasing from a zero demand to full demand. During the rotation of cam shaft 85, the lobe 91 raises push rod 93 which in turn raises switch arm 94 and causes the free end thereof to engage the latch 95 to move armature 96 against the bias of spring 99. In this manner, the switch arm 94 is again latched in its raised position. However, energization of field winding 84 continues by virtue of the maintaining circuit controlled by switch arms 102 and 103. When the cam shaft 85 has completed a full revolution, the lobe 92 raises push rod 101 which, in turn raises switch arm 102 from engagement with switch arm 103. Field winding 84 is thereby deenergized and the cam shaft has returned to the position shown in the drawings and remains in this position until electromagnetic coil 98 is again momentarily energized.

The circuit to electromagnetic coil 98 is controlled by a switch which comprises a stationary switch arm 115 and a movable switch arm 116. This energizing circuit is as follows: line 105, wire 106, wire 117, switch arms 115 and 116, wire 118, electromagnetic coil 98, wire 119 and wire 110 to line 111. Switch arm 116 is normally biased from engagement with switch arm 115 but is intermittently moved into engagement with switch arm 115 at frequencies which are varied by mechanism which will now be described.

Switch arm 116 extends in back of a ratchet wheel 120 which is pivoted or journaled at 121. Ratchet wheel 120 carries on its rear face two switch actuating buttons 122 and 123 which are adapted, upon clockwise rotation of ratchet wheel 120, to engage switch arm 116 to move the same into contact with switch arm 115. Counterclockwise movement of ratchet wheel 120 is prevented by a stop pawl 124 which is constantly urged into engagement with the teeth of ratchet wheel 120 by a compression spring 125. An actuating pawl 126 is biased into engagement with the teeth of ratchet wheel 120 by means of a compression spring 127 and is pivoted to an actuating arm 128 as indicated at 129, the actuating arm 128 being pivoted at the axis of ratchet wheel 120. A tension spring 130 tends to rotate actuating arm 128 in a counter-clockwise direction. Actuating arm 128 is provided with a laterally extending pin 131 which enters an elongated slot 132 formed in an actuating link 133. The other end of actuating link 133 is journaled on a crank pin 134 which is secured to a disc 135 that is rotatable with a gear 136. Gear 136 is driven by a motor rotor 137 through suitable speed reducing mechanism 138. Rotor 137 is provided with a field winding 139 which is constantly energized during the operation of the control system. A stop link 140, which is pivoted to actuating arm 128 as at 141, is provided with a plurality of stop surfaces 142, 143, 144, 145, 146, 147, 148 and 149. The upper end of stop link 140 is pivoted to a connecting link 150, the other end of which is 75

pivoted at a point directly above the axis of ratchet wheel 120 and which point is likewise preferably the pivotal point for stop pawl 124. Actuating arm 128 is slowly reciprocated about pivot 121 by virtue of rotation of disc 135 and its connection thereto by actuating link 133. Each clockwise rotation of actuating arm 128 advances ratchet wheel 120 (9 teeth for example) when the downward movement of stop link 140 is not restricted. However, if the movement of stop link 140 is restricted so that actuating arm 128 cannot move in a counter-clockwise direction the full amount allowed by actuating link 133, then in that event, the slot 132 of actuating link 133 will permit of relative movement between actuating arm 128 and actuating link 133. In this manner, by allowing stop link 140 to only move downwardly a small distance, the counter-clockwise rotation of actuating arm 128 will be relatively small and the clockwise movement thereof will be equally small so that ratchet wheel 120 is only moved forward a small number of teeth at a time. In this manner, by varying the movement of stop link 140 so that ratchet wheel 120 is moved larger or smaller numbers of teeth for every rotation of disc 135, the time intervals at which buttons 122 and 123 will be operated to move switch arm 116 into engagement with switch arm 115 may be varied.

The amount of movement allowed stop arm 140 is preferably varied automatically as a result of the change in one or more conditions which vary the amount of heating required by any particular zone. In the present embodiment of the invention, there is provided a vertical plate 155 which is connected to a plunger 156 that is positioned by the conjoint action of a pair of solenoid coils 157 and 158. The plate 155 is normally free to move back and forth but upon engagement by stop link 140, the plate 155 is moved downwardly into engagement with a stationary bracket 159 whereby undue strain is not placed upon plunger 156.

Solenoid coils 157 and 158 are connected in series across the secondary 160 of a step down transformer 161 having a high voltage primary 162. The junction of solenoid coils 157 and 158 is connected to a contact finger 163 by means of wires 164, 165 and 166 through a manually adjustable resistance 167. The contact finger 163 is controlled by thermostatic element 34 and sweeps across a resistance 168 upon changes in the outdoor temperature to which thermostatic element 34 responds. One end of resistance 168 is connected to the outer end of solenoid coil 157 through a rheostat 169 by means of wires 170 and 171. Similarly, the other end of resistance 168 is connected to the outer end of solenoid coil 158 through a rheostat 172 by means of wires 173 and 174.

Duct thermostat 38 is herein shown as comprising a thermostatic bellows 175 of well-known construction which moves a contact finger 176 across a resistance 177. Resistance 177 is connected in parallel with resistance 168 by means of wires 178 and 179. Contact finger 176 is connected to contact finger 163 by wires 180, 181 and through a switch 182. Switch 182 is a centrifugal switch controlled by the rotor 183 of the induction fan 36. Associated with rotor 183 is a field winding 184 which is controlled by a time controlled switch 185. Time controlled switch 185 is shown as being controlled by a cam 186 whereby the operation of the blower 36 may be discontinued during predetermined periods of the day or

night if it should be so desired. The circuit for field winding 184 is: line 105, wire 187, time controlled switch 185, field winding 184 and wire 188 to line 111.

Operation of the complete system

With the parts in the position shown in Fig. 2, the outdoor temperature is intermediate as indicated by contact finger 163 being in engagement with the center of resistance 168. Likewise, the average temperature of the various rooms is substantially that desired as indicated by engagement of contact finger 176 with the central portion of resistance 177. As a result, solenoid coils 157 and 158 are substantially equally energized so that plunger 156 assumes a central position and stop plate 155 is in such position that it will be engaged by stop 146 of stop link 140 upon the next succeeding downward movement thereof. Stop 146 allows actuating arm 128 to move downwardly sufficiently that ratchet wheel 120 will be advanced six teeth each time disc 135 makes a complete revolution. The ratchet wheel 120 is provided with 120 teeth and since there are two buttons 122 and 123, the ratchet wheel must be advanced 60 teeth for each closure of switch 115—116. With the ratchet wheel 120 being advanced at the rate of six teeth per revolution of the disc 135, which revolves at a speed of approximately one revolution for every 100 seconds, the switch 115—116 will be closed approximately every 17 minutes. Each time the switch is closed, electromagnetic coil 98 is energized to start cam shaft 85 on one of its cycles of rotation. During this cycle of rotation of cam shaft 85, the valves 30 and 26 are successively opened for periods of about two minutes, it requiring 5½ minutes for cam shaft 85 to make a complete revolution.

In this manner, steam is supplied for periods of two minutes each with intervals of approximately 15 minutes between these feeding periods for the particular prevailing outdoor temperature.

If the outside temperature should become very mild so that contact arm 163 moves to the lower end of resistance 168, solenoid coil 157 will be substantially short-circuited whereby the plunger 156 will move to the extreme right and stop plate 155 will be moved into the path of stop 142. Movement of actuating arm 128 will thereupon be greatly restricted so that ratchet wheel 120 will only advance two teeth per revolution of disc 135 with the result that switch 115—116 will only be operated every 50 minutes. In this manner, the intervals between the two minute feeding periods will be greatly increased but it will be noted that the steam feeding periods are of equal duration and that the variable is the interval between the steam feeding periods whereby a variable period is allowed for condensing of steam in the radiators and its dissipation to the rooms.

If the outside temperature should become extremely cold so that the contact finger 163 engages the upper end of resistance 168, solenoid coil 158 will be substantially short-circuited and the plunger 156 will move to the extreme left to bring stop plate 155 under stop 149. With the stop plate in this position, actuating arm 128 is not restricted whatsoever in its movement with the result that ratchet wheel 120 is advanced 9 teeth for each revolution of disc 135 with the result that switch 115—116 is closed approximately every eleven minutes.

In this manner, although the steam feeding periods are never varied in length, the intervals

between such periods are varied in accordance with the change in outdoor temperature so that the temperature of the various rooms should remain at the desired point.

5 The thermostat or controller 38 serves to modify the action of the outdoor thermostat or controller 33 according to variations in the average temperature of the rooms 28 and 32. When the contact finger 176 is contacting the central portion of resistance 177, the solenoid coils 157 and 158 are equally energized insofar as the controller 38 is concerned so that the respective energizations of the solenoid coils 157 and 158 will be dependent entirely upon the action of controller 33. However, if the average temperature becomes too high, contact finger 176 will move upwardly along resistance 177 and tend to energize solenoid winding 157 more highly than solenoid winding 158. The reverse action takes place if the average temperature becomes lower than that desired. In this manner, the outdoor controller 33 and the average temperature controller 38 cooperate to control the length of the periods between successive valve openings.

25 The use of an indoor temperature responsive device, such as average temperature controller 38, is particularly desirable since the outdoor thermostat 33 may be necessarily maintain the indoor temperature at the exact desired value 30 because it responds only to outdoor temperatures and only indirectly controls the indoor temperature. The inclusion of an indoor thermostat operates to offset any appreciable deviation of the indoor temperature from the desired value so 35 that the indoor temperature is maintained closer to the desired point that it might be maintained by the sole action of an outdoor thermostat.

The time switch 185 may be utilized to shut down the fan 36 at night, if desired. Whenever 40 rotation of fan 36 ceases, centrifugal switch 182 opens and disconnects contact finger 176 from the control system whereby average temperature controller 38 is rendered inoperative.

45 The rheostats 172, 167 and 169 are preferably controlled by a single manually operable member 190 and serve to introduce a variable amount of resistance in the control circuits for solenoid coils 157 and 158 whereby the position of plunger 156 for any given position of controllers 33 and 38 may be adjusted to properly correlate the control system to the particular steam heating system and building with which it is used.

50 From the foregoing description of the system of the present invention, it will be readily seen that the periods of feeding steam are always equal and the length of these periods must be determined for each particular installation so that they are only long enough to allow all of the radiators to become properly filled with steam at 55 which time the feeding periods should terminate. The control action is then obtained by varying the intervals between the steam feeding periods. In the specific embodiment herein described, the control system is so arranged that steam will be 60 fed at least every 50 minutes irrespective of the requirements. Such a feature is particularly desirable in heating hotels and the like wherein it is desired to maintain the radiators warm to the touch even in the mildest of weather so that the 65 guests will not obtain the impression that no heat is being furnished. For other types of control, it is highly possible that much longer intervals between the steam feeding periods would be 70 permissible.

75 It will also be noted that the present system

provides for the opening of a plurality of valves at spaced intervals rather than simultaneously in order that the relatively small supply of steam capable of being carried in the boiler will not be immediately exhausted before the automatic controls have a chance to begin generating more steam.

80 While a specific embodiment of the invention has been described, it is to be understood that many modifications could be made herein and 10 that the invention is equally applicable to temperature control systems other than heating systems and that at least some phases thereof are applicable to types of control systems other than temperature control systems. I therefore intend 15 to be limited only in accordance with the scope of the appended claims.

I claim as my invention:

1. In combination, a plurality of spaces, the temperature of which it is desired to control, a 20 plurality of temperature changing devices, at least one for each space, a supply of temperature changing fluid for said devices, fluid flow controlling means in control of the flow of fluid to said devices, temperature responsive means 25 responsive to the average temperature of said spaces, temperature responsive means responsive to some other temperature condition, and means controlled by the conjoint action of said temperature responsive means for operating the fluid 30 flow controlling means to permit flow of fluid to said devices for successive periods of equal duration and to prevent such flow for intervals of varying duration.

2. In a heating system, in combination, a plurality of spaces to be heated, a plurality of radiators, at least one for each space, a single valve in control of the flow of fluid to said radiators, means for opening said valve for recurring equal periods and for closing the same for intervals of 40 varying duration, said means including an outdoor temperature responsive thermostat and means controlled by the average of the temperatures of all of said spaces.

3. In combination, a plurality of spaces, the 45 temperature of which it is desired to control, a plurality of temperature changing devices, at least one for each space, a supply of temperature changing fluid for said devices, fluid flow controlling means in control of the flow of fluid to said devices, temperature responsive means responsive to the average temperature of said spaces, temperature responsive means responsive to some other temperature condition, means controlled by the conjoint action of said temperature 50 responsive means for operating the fluid flow controlling means to permit and prevent flow of fluid to said devices for total periods of varying duration and time controlled means for rendering one of said temperature responsive means 55 inoperative during predetermined periods.

4. In combination, a valve, means including a movable member arranged to initiate opening of the valve and to maintain the same open for a definite time, a constantly driven reciprocating 65 member, a driving connection between the reciprocating member and movable member, and a thermostat associated with said driving connection for varying the amount of movement transmitted to the movable member for each reciprocation of the reciprocating member whereby to vary the intervals between successive valve openings.

5. In combination, a valve means including a movable member arranged to initiate opening of 75

the valve and to maintain the same open for a definite time, a constantly driven reciprocating member, a driving connection between the reciprocating member and movable member and including a ratchet and pawl, and a thermostat associated with the ratchet and pawl and arranged to vary the number of teeth of the ratchet over which the pawl moves whereby to vary the amount of movement of the movable member for each complete reciprocation of the reciprocating member.

6. In combination, a plurality of spaces the temperature of which it is desired to control, means for changing the temperature of all of said spaces, temperature responsive means responsive to the average temperature of all of said spaces, means responsive to outdoor conditions and means controlled by the conjoint action of the temperature responsive means and outdoor condition responsive means for controlling the temperature changing means, and time con-

trolled means operative to render said temperature responsive means inoperative during predetermined periods.

7. In combination, a plurality of spaces the temperature of which it is desired to control, a plurality of temperature changing devices, at least one for each space, a supply of temperature changing fluid for said devices, fluid flow control means in control of the flow of fluid to said devices, temperature responsive means responsive to the average temperature of all of said spaces, temperature responsive means responsive to outdoor temperature, connections by which said temperature responsive means cooperate in operating the fluid flow controlling means to permit and prevent flow of fluid to said devices for varying periods, and time controlled means arranged to render the average temperature control means inoperative to control the fluid flow controlling means during predetermined periods. 10 15 20
